DESIGN FOR A TOY ANIMAL FIGURE

Ernesto Peruggi, Brooklyn, N. Y., assignor to The Lionel Corporation, New York, N. Y., a corporation of New York

Application June 6, 1944, Serial No. 113,876

Term of patent 7 years

(Cl. D34—2)

To all whom it may concern:

Be it known that I, Ernesto Peruggi, a citizen of the United States of America and a resident of Brooklyn, in the county of Kings, city and State of New York, have invented a new, original, and ornamental Design for a Toy Animal Figure, of which the following is a specification, reference being had to the accompanying drawing forming a part thereof.

In the drawing:

The essential features of the design reside in the parts shown in full lines.

I claim:

The ornamental design for a toy animal figure, as shown and described.

ERNESTO PERUGGI.
